UNITED STATES PATENT OFFICE.

GEORGE E. HULSE, OF NEW HAVEN, CONNECTICUT, ASSIGNOR TO SAFETY CAR HEATING & LIGHTING COMPANY, A CORPORATION OF NEW JERSEY.

FLEXIBLE ELECTRICAL CONNECTION.

Application filed January 27, 1922. Serial No. 532,119.

This invention relates to construction for flexible electrical connections and the like and, with regard to certain more specific features, to the construction of insulated 5 flexible electrical connections designed for use under conditions such as may subject them or their insulation to wear and deterioration due to exposure to adjacent moving elements. One of the objects thereof is 10 to provide a strong and dependable construction of the above nature adapted successfully to withstand the conditions of hard practical use. Another object is to provide a simple and efficient construction of the 15 above nature in which the insulation is not only flexible but well adapted to resist wear and in which the danger of the electrical conductor thereby becoming exposed is reduced to a minimum. Other objects will be 20 in part obvious and in part pointed out hereinafter.

The invention accordingly consists in the features of construction, combinations of elements and arrangement of parts which 25 will be exemplified in the structure herein-after described and the scope of the application of which will be indicated in the following claims.

In the accompanying drawing in which is 30 shown one of various possible embodiments of this invention:—

Figure 1 is an elevation of a flexible electrical conductor and associated parts partly in section and with certain parts broken 35 away.

Figure 2 is a detached elevation of one of the associated parts shown in Fig. 1; and

Figure 3 is a sectional view similar to the right-hand side of Fig. 1, but showing certain parts more in detail.

Similar reference characters refer to similar parts throughout the several views of the drawing.

As conducive to a clearer understanding 45 of certain features of this invention it may be here noted that in many types of flexible conductors now ordinarily in use a flexible covering of insulating material is employed to encase the conductor. In application of the flexible conductor to devices such as 50 leads for generator brushes and the like, wherein the conductor is continually subjected to twisting and distortion and the liability of rubbing against adjacent objects, 55 this flexible casing often wears through and

exposes the conductor. The provision of a construction of this general nature which will obviate this danger and provide an efficient, reliable and flexible protection for the conductor is among the dominant aims of 60 this invention.

Referring now to the drawings in detail and first to Fig. 1, there is shown an electrical conductor 10 preferably of a stranded construction to provide a flexible electrical 65 connection. The conductor 10 may be covered by suitable inner insulating means 11 such as rubber with cotton fabric superimposed thereon. The conductor 10 may be provided with terminal connections such as 70 14, one of which is shown in section in Figure 1 and may be noted to have a conical seat 16 terminating in an aperture 17 adapted to receive the end of the conductor 10. A plug 18 having a conical projection as 75 19 adapted to mate with the conical seat 16, may be threaded into the terminal connection 14 at a point opposite the aperture 17. In operation, when plug 18 is screwed into position, the conical projection 19 may engage 80 the end of the stranded conductor 10, separating the strands radially and securely binding them against the conical seat 16, thereby forming a rigid electrical connection between the conductor 10 and the terminal 85 connection 14. The terminals 14 are shown each provided with a drilled flange 15 by means of which electrical connection may be made to any desired element.

At 12 is shown a spirally wound outer 90 covering, preferably of a non-conductive wear-resisting material such as leather which envelops the inner insulation 11 and the flexible conductor 10 encased therein. This protective covering 12 being preferably of 95 a non-abrasive yielding nature will not wear the inner insulation 11 in case the conductor is bent and twisted in service and provides additional insulation which will tend to nullify the effect of a break in the inner insulation. 100 As shown at 20 in Fig. 1, the ends of the outer insulating covering 12 contact snugly with terminal connections 14 thereby to insure complete encasement of the inner insulation 11. Fig. 2 shows a detached section of the outer insulation 12 and a means at its end for securing the latter to terminal connections 14 as at 20 of Fig. 1. 105 This attaching means may comprise a metal strip or wire 21 attached to covering 12 pref- 110

erably by piercing through the covering at a point as 22 adjacent its end, the wire or strip being adapted to pass through the aperture 17 of the terminal 14 and to be held between the conical surfaces 16 and 19 in conjunction with the strands of conductor 10, as shown in Figure 3. Thus the outer protective insulation 12 is effectually secured in its position about the inner insulation 11 and there is no possibility of its slipping along the conductor and away from the terminal connections 14.

It will thus be seen that there is provided a construction in which the several objects of this invention are achieved and that the same is well adapted to meet the exacting conditions of hard, practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

25 I claim as my invention:—
 1. In a construction of the character described, in combination, a flexible stranded electrical conductor, an insulating covering about said conductor, an outer protective casing exterior of said insulation comprising a spirally wound leather strip, a terminal connecting device having a passage thereinto for receiving the end of said conductor and a threaded member adapted to clamp said con-

ductor end against a wall of said passage to 35 secure said conductor to said terminal device and make electrical connection therebetween, and a metal strip secured to the end of said leather strip, entering said passage with said conductor end clamped therewith by said threaded member to hold said spiral covering in place.

2. In construction of the character described, in combination, an electrical conductor, a terminal connection for said electrical conductor including a conical seat terminating in an opening through which said electrical conductor is inserted and a conical plug threaded into said terminal connection and adapted to bind the end of said electrical 45 conductor against said conical seat, a protective covering encasing said electrical conductor and comprising a spirally wound strip of yielding non-metallic material, and a metal strip secured at one end to said 50 spiral strip and projecting therefrom adjacent said terminal connection and adapted to be held between said conical seat and said conical plug in conjunction with the end of said electrical conductor thereby to secure 55 said protective covering in position against removal from said electrical conductor.

In testimony whereof, I have signed my name to this specification this 20th day of January, 1922.

GEORGE E. HULSE.
